UNITED STATES PATENT OFFICE.

JOHN GILBERT FYE, OF OLLIE, IOWA.

VALVE-SPRING-LIFTING DEVICE.

Application filed April 19, 1921. Serial No. 462,533.

To all whom it may concern:

Be it known that I, JOHN GILBERT FYE, a citizen of the United States, and resident of Ollie, in the county of Keokuk and State of Iowa, have invented a certain new and useful Valve-Spring-Lifting Device, of which the following is a specification.

The object of my invention is to provide a simple, durable, and inexpensive device for 10 lifting the valve springs of valve stems such as is used on the mushroom valves of the ordinary engine for automobiles so that the pins beneath the spring may be easily and quickly removed from the stem.

15 More specifically it is the object of my invention to provide a lifting device for valve springs having improved means for engaging the springs so that the device may be adapted to be placed in position on valve 20 springs that are in difficult positions to reach. My still further object is to provide in a valve lifting device having pivoted lifting arm improved means for actuating the arms so that the said arm may be elevated any desired amount to adapt the 25 device to be used in connection with engines of different types and when so lifted they will be automatically retained in their lifted position at the will of the operator.

30 My invention consists in the construction, arrangement and combination of the various parts of the device, whereby the objects contemplated are attained, as hereinafter more fully set forth, pointed out in my claims, and 35 illustrated in the accompanying drawings, in which:

Figure 1, is a side elevation of my improved valve spring and lifting device showing the manner in which it is applied to a 40 valve spring. Said valve spring being shown in position on the valve stem mounted in a segmental portion of an engine block.

Figure 2, is the plan view of my improved valve spring lifting device.

45 Figure 3, is a sectional view taken on the line 3—3 of Figure 1.

My improved device comprises a tubular arm, 10, having a bifurcated portion 11 at one end and two plates 12, riveted to the opposite sides and substantially parallel to each other. Pivotal mounted between the plates 50 12 is a second tubular arm 13 of substantially the same length as arm 10, and provided with a bifurcated portion 14 at its free end. Both 55 of the arms 10 and 13 are curved near their free ends for the purpose of forming the de-

vice so that it will more readily be adapted to be placed in the proper position for lifting the valve spring. Each of the bifurcated portions 11 and 14 is provided with a pivoted and forked plate 15. The space between the fork members of said plate is somewhat wider than the diameter of the ordinary valve stem and in length substantially equal to, or greater than the diameter of 60 the spring, to engage washers 16, which are usually of substantially the same diameter as the spring. One of these springs is indicated by the numeral 17 in Figure 1 of the drawings. The upper end of the spring 65 usually rests against the overhanging valve chamber 18 which is provided with a valve not shown in the drawings, said valve having a downward extending stem 19, which extends downwardly through said spring, 70 the lower end of which rests on said washer. The lower end of said stem 19, rests on the end of a push rod 20. The washer 16 is designed to rest normally on the pin 21, which has to be removed before the valve on the stem 19 can be removed as the said valve is removed by pulling the stem upwardly through the valve chamber and it is therefore necessary to elevate the said washer a slight distance so that the said pin 21 may be 80 85 easily removed. This is accomplished by placing one of the fork members, 15, on the upper portion of the boss 22 in which the push rod 20 operates and the other beneath the washer 16 with the fork members straddling the rods 19 and 20 respectively. The lower end of the spring 17 together with the washer 16 may be elevated by separating the members 15. This I have accomplished by 90 separating the arms 10 and 13. To separate the said arms I have provided a lever device, 23, having formed on one end a triangular plate 24. Mounted in one end of the said plate 24, I have provided rivets 25, which are of a length slightly greater than the diameter of the members 10 and 13, and are designed to carry a similar plate 26 which is 95 arranged parallel to the said plate 24.

In the apex end of the plates 24 and 26 I have provided a series of openings 27. The 105 openings of one plate is in line with those of the opposite plate. A corresponding set of these openings is designed to receive a detachable rivet 28. The said openings 27 are substantially in line with each other and said line extends substantially between the rivets 25 so that the said rivets are arranged in 110

triangular form, the distance between the rivets 25 is considerably less than the distance between the rivets 25 and the rivet 28. In fact the distance between the outsides of 5 the rivets 25 should be substantially equal to the distance between the members 10 and 13, when said members are in a closed position.

The tool 23 is applied to the members 10 and 13 in such a manner that the rivets of 10 the said tool will rest transversely between the members 10 and 13, with the said members between the plates 24, with the rivets 25 in a plane substantially perpendicular to the said members 10 and 13.

15 When it is desired to separate the members 15, a swinging movement is imparted to the handle 23, which will cause the rivets 25 to rest in a plane parallel with the member 10 and the rivet 28 adjacent to the member 13. This will cause the said members 10 and 13 to be separated due to the fact that the distance between rivets 25 and the rivet 28 is greater than the distance between said rivets 25.

20 It is evident that when the device assumes the position shown in Figure 1 that the said arms will be held separated on account of the triangular arrangement of the rivets. By moving the rivet 28 from one set 25 of openings 27 to another the amount of lift between the members 15 may be varied. A further variation may also be imparted by moving the tool 23 either toward or from the pivoted ends of the member 13. By 30 pivoting the plates 15 the tool is more readily adapted to engage certain valve springs for instance the end valve springs usually rest on a corner adjacent to the gear casing or other similar obstructions. For holding 35 the members 10 and 13 toward each other I have provided a coil spring 13^a. This also serves to hold the handle device 23 in position between said arms to prevent said handle from falling out.

40 Thus it will be seen that I have provided a valve spring lifting device which may be easily and quickly placed in position and when placed in position it may be easily operated, and when moved to its operated position it will automatically retain that position until the handle 23 is moved in the opposite direction.

45 One advantage of the separate handle member 23 lies in the fact that the said member may be applied to the tool at any 55 position along the straightened portions of the members 10 and 13 and the device operated. This is quite an advantage over a fixed pivoted member for operating the 60 lifting arms, due to the fact that it often happens that certain obstructions are so positioned that a fixed operating mechanism

would be in such position as to engage the said obstruction. By adjusting the rivet 28 the handle 23 may be adapted to be operated either near the pivoted ends of the lifting members or the lifting ends of said members.

65 I claim as my invention:

70 1. An improved valve spring lifting device comprising two arms pivoted together near one end, and a spreader for said arms comprising a handle and a body portion, the body portion being formed with two plates spaced apart from each other and capable of being inserted between the arms when they are spread and to receive the arms between the plates when the arms are brought toward each other, a fixed arm engaging member between said plates to engage one of the arms, and an adjustable arm engaging member between said plates to engage the other one of said arms, the adjustable member being capable of movement toward and from the fixed member.

80 2. An improved valve spring lifting device comprising two arms pivoted together, a forked and pivoted member at the free end of each of said arms, a detachable spreading tool designed to be inserted from the side between said arms and to separate 90 the same by rotary movement, and to hold the arms in a separated position, said separating tool comprising two parallel plates spaced apart a distance slightly greater than the diameter of said pivoted arms, whereby the arms may be slidingly received between the plates, a handle secured to one of said plates, two fixed rivets extended through said plates for holding them in their relative positions, and a detachable rivet, said rivets being arranged in a triangular form with the distance between the detachable rivets and the fixed rivets greater than the distance between said fixed rivets, for the 95 purposes stated.

100 3. An improved valve spring lifting device comprising two arms, two parallel plates mounted on opposite sides of said arms at one end, means for fixing one of said arms in position between said plates, means for pivoting the other of said arms in position between the said plates, and a spreader device for said arms comprising two plates 110 slidably mounted on opposite sides of said arms, a handle secured to one of said plates, and a triangularly shaped device between the plates of the spreader device designed to engage adjacent surface of said arms, said triangular device being relatively short at one side and relatively long at the other two sides, for the purposes stated.

115 120 Des Moines, Iowa, April 7th, 1921.

JOHN GILBERT FYE.
